UNITED STATES PATENT OFFICE.

WILLIAM S. WILKINSON, OF AURORA, SOUTH DAKOTA.

BELT-COUPING.

1,075,078.

Specification of Letters Patent.

Patented Oct. 7, 1918.

Application filed November 14, 1912. Serial No. 731,444.

To all whom it may concern:

Be it known that I, WILLIAM S. WILKINSON, a citizen of the United States, residing at Aurora, in the county of Brookings and 5 State of South Dakota, have invented certain new and useful Improvements in Belt-Couplings; and I do declare the following to be a full, clear, and exact description of the invention, such as will enable others 10 skilled in the art to which it appertains to make and use the same.

This invention relates to improvements in belt couplers and more particularly to the types employing a hinge connection.

15 One object of the invention is to provide a very simple and efficient hinge or coupler which will securely lock the two ends of the belt together.

Another object is to provide means for 20 preventing the ends of the pintle from coming in contact with objects such as belt shifters along its course of travel.

A further feature of the invention is in 25 the construction of a hinge or coupler of the character described, whereby the united ends of the belt provide means for preventing the pintle from turning and thereby released during the travel of the belt.

With these objects in view, the invention 30 resides in certain novel features of construction and combination of parts which will be clearly defined in this specification and in the claim appended hereto.

In the drawings: Figure 1 is a perspective 35 view of my coupler and the joined ends of the belt connected thereby. Fig. 2 is a plan view thereof. Fig. 3 is an edge view partly in section. Fig. 4 is a transverse section taken on the line 4—4 of Fig. 2, and Figs. 5 40 and 6 are horizontal sectional views showing the manner in which the pintle must be removed.

By reference to the accompanying drawing, it will be seen that my invention comprises two companion hinge members 1 and 45 2, each of which is formed in a well known manner by bending a metal plate upon itself and cutting notches 3 therein for the purpose of receiving the loops 4 on the adjoining member. It is to be further noted that the loops on each member engage the notches on the opposite member very loosely, thus allowing a slight lateral movement which is imperative in removing the pintle

5 hereinafter described. This pintle 5 is of 55 a length approximately equal to the width of the hinge members above described and is adapted for removable engagement with the loops 4, whereby a flexible separable connection is provided. A lug 6 projects laterally 60 from one end of the pintle and is adapted to come into engagement with one of the outer loops 4 and thus prevent the removal of said pintle provided it be held from turning. The gist of the present invention resides in 65 the specific means for preventing this pintle 5 from turning. This is accomplished by forming an elongated head 7 (of less width than the belt) on the end of the pintle opposite the lug 6 and so securing the ends of 70 the belt 8 between the clamping plates 1' and 2' that the edges thereof project beyond the edges of said plates and the space between these joined ends will be slightly less than the length of the head 7. With this 75 structure it will be clearly seen that when the head of the pintle is turned to bring it in line with the belt, the ends of the head will embed themselves in the ends of the belt, thus forming an efficient lock for preventing 80 the casual turning of the pintle and probably the loss of the same.

When it is desired to separate the coupler as for removing the belt in such a place that would not permit slipping it from the pulley, my device is very convenient as all that is necessary is to turn the head of the pintle until the lug 6 is out of engagement with the outer loop 4 and said pintle is free to move laterally as shown in Fig. 5, until the 85 next loop interferes. Then by giving the pintle another half turn, the lug 6 will travel in the spaces between two of the loops 4 and the pintle will then be free to be pulled farther out of the loops as shown in 90 Fig. 6. It will be seen that by repeating this movement, the pintle may be entirely removed and by reversing said movements, it may be inserted.

Particular stress is laid on the projecting 100 of the belt beyond the edges of the coupler, thereby not only forming an efficient lock for the pintle of the coupler, but forming a protection for the projecting ends thereof which is very important in cases where a 105 forked belt shifter is employed.

From the foregoing description taken in connection with the accompanying draw-

ing, the construction and operation of the device will be clearly understood without requiring a more extended explanation.

What is claimed as new is:—

- 5 The combination with the meeting edges of a belt, of a coupler connected thereto and composed of two hinge sections each having parallel attaching plates, the latter being narrower than the width of the belt
- 10 whereby the edges of the belt are exposed beyond the plates, hinge loops connecting said plates and laterally spaced a greater distance than the width of said loops, a pintle removably engaged with said loops
- 15 and having a laterally projecting lug on one

end and an elongated head on its opposite end, the opposite ends of which head are adapted to be turned into binding and yielding engagement with the unprotected connected ends of the belt, whereby the pintle 20 is prevented from turning and the head thereof protected by the thickness and edges of the belt.

In testimony whereof I have hereunto set my hand in presence of two subscribing 25 witnesses.

WILLIAM S. WILKINSON.
